UNITED STATES PATENT OFFICE.

FRANK GUNN FARNHAM, OF HONESDALE, PENNSYLVANIA.

POLISHING-WHEEL.

SPECIFICATION forming part of Letters Patent No. 709,312, dated September 16, 1902.

Application filed October 28, 1901. Serial No. 80,280. (Model.)

To all whom it may concern:

Be it known that I, FRANK GUNN FARNHAM, a citizen of the United States, residing at Honesdale, Pennsylvania, have invented certain new and useful Improvements in Polishing-Wheels, of which the following is a specification.

My invention relates to improvements in cleaning and polishing wheels of that nature in which cloth is used as buffing or polishing material. These have generally been constructed by securing either single strips or folded strips to a suitable hub or support, the strips overlapping each other and radiating from the hub to form a disk or wheel. Wheels formed from single strips of fabric are not durable, as the edges ravel very rapidly on both sides and on the end, so that the lifetime of the wheel is very short. The wheel composed of folded strips is more durable, but can be run only in one direction, owing to the fold in the cloth, as if the wheel is turned so that the cloth progresses with the fold or apex backward it catches the material operated upon in the fold.

The object of the present invention is to provide a brush which will avoid these disadvantages and which will be durable and effective and which may be run in either direction, thus prolonging the life of the wheel.

I have illustrated the invention in the accompanying drawings, in which—

Figure 1 is a side elevation of a brush-wheel, and Fig. 2 is a sectional view. Fig. 3 is a detail view of one of the tubes. Figs. 4, 5, and 6 are detail views of modifications. Fig. 7 is a view of a modified form of brush.

Referring more particularly to the figures, the wheel designated in Fig. 1 is composed of a plurality of radiating sections of cloth at *a*, which overlap each other and which are securely cemented to each other. Their inner ends abut against the central disk *b* and, if desired, at intervals disks of cloth, paper, or the like may be interposed, as shown at *c* in Fig. 2. Each of these cloth sections consists of a tube of seersucker or like material, which may be either a woven tube or a sewed tube, as desired, and the whole is strengthened by a line of stitching *a'*. In case a sewed tube is used it is preferable to turn the tube

inside out, so as to bring the seam on the inside, as shown in Fig. 3. Instead of using a single tube, as shown in Figs. 1, 2, and 3, I may use cloth sections of the form shown in Fig. 4, in which it will be seen that a piece of cloth is folded upon itself and stitched at *c* at a distance from and parallel to the edges. This provides a tubular portion *c'* and two loose flaps *c''*. When the tube is reversed, as before referred to, the flaps or wings *c''* are brought on the inside and are protected against raveling and catching by the encircling tube, while at the same time they add body to the sections. This gives a heavy body of working material. If desired, I may use two tubes of either of the forms described, as indicated in Fig. 5. In this case one of the tubes, *d*, is made shorter than the other, *d'*, and they are secured together by stitching *d''* at the inner edge of the shorter one. The projecting portion *d''* of the longer one only is cemented to the adjoining parts. This gives me a very narrow hub with a heavy working body, which is very desirable for many classes of work. If desired, I may place inside of each tube any kind of fiber or yarn, as illustrated at *e* in Fig. 6. It will be understood that these wheel-sections are to be secured upon suitable supports or carriers and operated in the manner described by patents of the United States granted to me April 30 and July 2, 1901, and numbered, respectively, 673,119 and 677,502. If desired, I may reinforce the tubes composing the brush by a cloth disk *B* on each side, as indicated in Fig. 7, each disk or reinforce being composed of two circular pieces of cloth stitched together by lines of stitches, (indicated at *B'*.) This is advantageous in stiffening the brush for certain kinds of work. In this sectional form of tubular brush it is not necessary that they should be nailed together, as the collars hold them in place on the sleeve. Brushes of this class, called "textile brushes," are apt to wear beveling or hollow. When this occurs, the operator can remove the sections from the sleeve in a moment and replace them again, thus getting an even wear to all the edges. A brush made up from these tubes I find has about double the wear in it that there is in a brush made from similar goods, but having

more than one raw edge, besides giving a long smooth silk-like knap, which is desirable for fine footwear. At times when these brushes are used for bottoms and a lighter brush is required I prefer not to reverse the tube.

I claim—

1. A ring or section for a polishing-wheel comprising a plurality of projecting bunches, each of said bunches comprising a tube of textile material, substantially as described.
2. A ring or section for a polishing or cleaning wheel consisting of a series of independent projecting bunches, each of said bunches consisting of a folded material sewed near its center to form a tube and free edges, the tube being turned inside out to bring said free edges within the tube to serve as a filler therefor, substantially as described.
3. A ring or section for a polishing or cleaning wheel comprising a plurality of tubes of textile material secured to a suitable carrier and an independent tube secured separately

to each of said main tubes, substantially as described.

4. A ring or section for a polishing-wheel comprising a plurality of tubes of textile material and reinforcing-disks of textile material, substantially as described.

5. A ring or section for a polishing-wheel comprising a plurality of tubes of textile material, said tubes being stitched together, substantially as described.

6. A ring or section for a polishing-wheel comprising a plurality of tubes of textile material and reinforcing-disks of double textile material stitched together, substantially as described.

In testimony whereof I affix my signature in presence of two witnesses.

FRANK GUNN FARNHAM.
